SEALING AND DISPENSING DEVICE
Joseph J. Mancusi, Jr., Eastchester, N.Y., assignor to
Chapman Machine Company, Inc., Mount Vernon,
N.Y.

Filed Mar. 31, 1958, Ser. No. 725,045
6 Claims. (Cl. 222—207)

This invention relates to devices for sealing containers against the loss of fluids as by evaporation or run out or leakage upon accidental tilting and the contamination of fluids as through oxidation upon contact with air. More specifically it relates to such a sealing device which is automatic or self-opening and self-closing.

Containers are conventionally made with openings adapted to be closed off by covers of one kind or another. Such openings are often in a container neck, adapted to receive a sealing cap and secure it as through threads. The cap is manually unscrewed from the neck to permit pouring and manually reseated to seal the fluids in the container.

An object of this invention is to provide a sealing device which obviates the need for manual handling of the cap and speeds up use of the fluid contents of the container.

Another object of the invention is to provide a sealing device which can be permanently placed on a fluid container to render it safe at all times from leakage due to accidental tilting.

A further object of the invention is to provide such a sealing device which will also prevent evaporation of the fluid in the container and contamination of the fluid within the container by elements normally present outside thereof.

Still another object of the invention is to provide a sealing device which is inexpensive and easy of construction and simple and trouble free in operation.

The invention makes advantageous use of the creation of a pressure differential to open automatically a sealing device to permit the dispensing of fluids and of the elimination of the pressure differential to close automatically the sealing device. To this end, the sealing device is provided with a disc sealing element adapted to cover the opening in the neck of a container. Suitable openings therethrough would permit the passage of the container's fluid contents. Seated on the disc sealing element is a diaphragm valve element. The periphery of the valve element is disc-like and rests flush upon the exposed surface of the disc sealing element. Openings extending through the periphery of the valve element align with the openings in the disc sealing element to pass the container contents.

The central part of the valve element comprises a raised portion. This raised portion is movably supported upon the disc-like periphery of the valve element by a continuous thin sheet. The sheet is sufficiently flexible to act as a bellows or diaphragm operable to raise or lower the central raised portion upon the occurrence or disappearance of a difference in the pressures obtaining in the areas above and below the continuous thin sheet.

The sealing device is completed by a perforated cap which not only cooperates with the raised portion of the valve element to perfect the seal, but also acts to confine the elements of the sealing device in proper working relation to each other and additionally to the opening formed in the container. The perforation in the cap is centrally located so as to cooperate with raised portion of the valve element. The perforation and the raised portion are of such size as to permit the latter to close off the former. It may be more expedient, depending on the fluids being sealed and the materials being employed in the sealing device, to mount a centrally perforated rubber gasket on

2

the interior of the cap. Thus the raised portion of the valve element would cooperate with the perforation in the rubber gasket to form a more perfect seal. Bias either inherent in the valve element thin sheet or obtained through a compression spring disposed between the disc sealing element and the valve element raised portion would urge the raised portion into sealing engagement with the cap or, alternatively, with the rubber gasket.

A sealing device such as described may be advantageously applied to containers of the flexible type. When the container is inverted to place the outlet at the bottom, fluid would flow down through the one or more openings in the disc seal and the aligned openings in the valve element periphery into the space between the valve element and the cap. Now the bias urging the valve element raised portion into sealing engagement may be such as to allow the weight of the fluid within the container to force the now inverted raised portion upward from its sealing engagement from the cap or gasket. Fluid would then be dispensed through the cap opening. On the other hand, the bias urging the raised portion to its seat may be such that only additional pressure resulting from squeezing the container together will operate to unseat the raised portion to provide fluid dispensing.

These and other features, objects, and advantages of the invention will become apparent from a reading of the following specification when considered with the accompanying drawings which show, by way of example, a preferred embodiment of the invention.

30 In the drawing:

FIG. 1 is a view in perspective of a flexible container mounting a sealing device constructed according to the invention.

FIG. 2 is a view showing the sealing device of FIG. 1 in vertical cross-section.

FIG. 3 is an enlarged cross-sectional view showing the valve element of the sealing device of FIG. 2 in its normal condition.

Referring more particularly to the drawing, there is shown in FIG. 1 a metal container 10 of conventional construction. The broad, flat sides of such a container may be grasped and pressed towards each other to develop the pressure on the fluid contents necessary to force them through the sealing device constructed according to the invention. This sealing device, generally designated by the numeral 12, is shown secured in place on the upper surface of the container 10. This upper surface may have its outlet formed with a neck 13 having threads on its outer periphery. Such a neck may come equipped with the sealing device, or perhaps with the usual cap which is removed by the user and replaced with applicant's novel sealing device.

The sealing device 12 is more fully shown in FIG. 2. It includes a cap 14 of metal or plastic which houses the other elements of the sealing device and constitutes the means for holding the sealing device in place with respect to the outlet of the fluid container 10. To accommodate a threaded neck, the lower end of the cap 14 is threaded. The cap would be screwed down upon the neck until the upper end of the latter came into abutting relationship with the lower surface of a disc seal 16.

A disc seal 16 will seat on the upper edge of the container neck and may be made of a plastic material chemically resistant to the container contents. Near its periphery it is formed with one or more openings 18, the number and size of which are dependent on the rate of fluid flow desired from the container 10.

Above the disc seal 16 in the sealing device 12 is a valve element 20 (FIGS. 2 and 3) also preferably formed of a chemically resistant plastic which may be extruded to form the valve element. The periphery 22 of the valve element 20 is disc-like and serves to support the element

20 in place upon the disc seal element 16. On its lower surface it rests upon the upper surface of the disc seal 16. On its upper surface it abuts the lower side of a gasket 24 formed of neoprene or rubber and resting on its upper surface against the underside of the cap 14.

The periphery 22 is formed with a number and size of openings 26 conforming to the number and size of openings 18 in the disc seal 16. The valve element is so seated with respect to the disc seal 16 as to align the respective openings. Above the openings 26 as at 28 the periphery 22 is cut away to form a chamber 28 to receive the radially inward flow of fluid which would flow down through the openings 18 and 26 when the container 10 is inverted.

The central part of the valve element comprises a continuous thin sheet 30 which is a continuation of the periphery 22 and a rounded raised portion or poppet 32 also of the same material. The normal relationship of the parts of the valve element is shown in FIG. 3. The continuous thin sheet 30 may be seen as consisting of an upwardly and inwardly directed portion extending from the point of juncture with the upper interior corner of the periphery 22 lying below the cutaway chamber 28 and of a radially inwardly directed portion merging into the centrally located raised portion 32. The continuous thin sheet acts as a diaphragm or bellows yieldably supporting the raised portion 32. This enables the normal position (FIG. 3) of the raised portion with respect to the rest of the valve element 20 to be so designed that when the parts of the sealing device are assembled (FIG. 2) the raised portion will seat itself in the outlet opening 34 formed in the gasket 24 to seal the container fluid contents against escape.

To prevent damping of the up and down action of the raised portion, the area below the thin sheet is vented through an inverted V-groove 36 in the lower surface of the periphery 22 of the valve element 20. Since the seal with the can 10 is made between the container neck and the disc seal 16, it follows that the groove 36 will communicate with the atmosphere through the small space obtaining between the edge of the disc seal 16 and the side of the cap 14 and the small interstices always existing between the threads of the container neck and the cap.

The normal bias in the thin sheet 30 will act to retain the raised portion on its seat. However, greater stability and reliability of operation may be obtained through the use of a compression spring 38. This spring is held in place between a hole 40 formed in the upper surface of disc seal 16 and a hole 42 formed in the underside of the raised portion 32. The value of the spring is so chosen as to enable ready collapse thereof when manual pressure is applied to the sides of the flexible container 10.

The opening 34 of the gasket 24 coincides substantially with an opening 44 formed in the center of the cap 14. Thus when the raised portion 32 is moved away from its seat in the opening 34 of the rubber or neoprene gasket 24, fluid dispensing may be accomplished. Such dispensing would be from the area in the cutaway chamber 28 in the valve element 20, through the gasket opening 34 and the cap opening 44.

A sealing device, such as disclosed, may be marketed installed or the container the dispensing of whose fluid contents it will control. Preferably, however, it would be packaged as an adjunct to a sealed container, the neck on the container being closed off by a conventional unperforated cap. Then too, the sealing device may be sold separately to enable it to be placed on containers marketed without applicant's sealing device.

A container having applicant's sealing device retains all of the advantages present in the usual manually removable cap. Thus, leakage from the container, including the evaporation of liquid contents, will at all times be prevented especially if the bias urging the raised portion 32 to its seat is selected so as to prevent the mere weight of the fluid contents from unseating the raised portion 32

when the container is inverted. Of course, the bias may be so chosen as to permit dispensing merely by inversion of the container.

In the embodiment disclosed, dispensing is effected by compressing the sides of the container 10 after inverting it. Upon the inversion, fluid, under the influence of gravity, would have filled the cutaway chamber 28 of the valve element 20 by passing downward through the aligned openings 18 and 26 in the disc seal element 16 and valve element 20 respectively. The compression of the container sides develops pressure upon the container contents. This pressure is transmitted down through all of the fluid and is present too in the fluid in the cutaway chamber 28. Now the thin sheet 30 has been pointed out as being diaphragmic in nature and under the pressure developed in the fluid in the cutaway chamber 28, deflects upwardly to carry the raised portion or poppet 32 out of the gasket opening 34. Fluid may then pass out through the openings 34 and 44.

It should be noted that the action of the diaphragm 30 was not hampered by the contents in the area beneath it. That is so because this area is vented to the atmosphere by the groove 36 and the interstices between the container neck 13 and cap 14 threads. Restoration of the diaphragm will be facilitated by this venting, too.

Flow of fluid from the sealing device will continue as long as sufficient pressure is maintained on the container contents and the fluid in the cutaway area 28. To this end the number and size of the sets of aligned openings 18 and 26 must be sufficient to enable a volume of fluid flow greater than that which escapes through the openings 34 and 44 for otherwise there would be a pressure drop in the cutaway area 28 enabling the spring 38 to move the diaphragm to where the raised portion 32 seals the opening 34. If the number and size of the openings 18 and 26 is insufficient, dispensing would at best be intermittent. Of course this type of action may be desired in some applications.

Normally, dispensing will cease when the pressure on the fluid contents subsides. This arises either through the release of applied pressure on the container sides permitting them to restore and relieve fluid pressure or through the dispensing of an amount of fluid approximating the reduction in container volume affected by compression of the container sides. In either event a reduction in fluid pressure allows the diaphragm to restore under the bias action and thereby carry the raised portion back into its seat in opening 34.

Return of the container sides towards their normal positions tends to create a vacuum or pressure less than atmospheric inside the container, which, if the container contents are a non-volatile liquid, would delay or prevent full restoration. Now it is possible that the vacuum might be eliminated through the action of atmospheric pressure forcing air into the container through the openings 44 and 34 and alongside the raised portion 32. Where a sealing device is designed to fit a particular container, resort to such operation may be had.

However, it is generally more expedient to employ vent holes in the top of the cap 14 and the gasket 24. Thus two vent holes 46 (FIGS. 1 and 2) may be formed in the top of the cap 14 and on radially opposite sides of the dispensing opening 34. Now, as has been observed before, the gasket 24 is formed of a flexible material such as rubber or neoprene and mounted in the sealing device by being clamped at its edges between the periphery 22 of the valve element 20 and the underside of the top of the cap 14. Thus when a vacuum or low pressure is created within the container 10, the gasket portion above the valve element cutaway chamber 28 will be moved away from the underside of the cap top by action of atmospheric pressure against the upper side of the gasket. Vents such as 48 formed in the gasket so as to be non-aligned with the vents 46 in the cap top, would now be uncovered to allow the rela-

tive free entry of air into the container, thereby facilitating immediate restoration of the container sides upon release. Of course, once the vacuum has been relieved, the gasket, being resilient, restores into nesting engagement with the cap top to seal the container and prevent vapor loss.

Evidently, then, applicant has provided a self opening and self closing or automatic sealing device. When a container embodying it is held so that the fluid contents contact the sealing device, dispensing may be effected either from the weight of the fluid or from the build up of pressure as by the squeezing together of the container sides. Leakage due to accidental tilting of the container is prevented where the sealing device is designed to require pressure over and above the weight of the container fluids. Loss of fluids by evaporation too is prevented; yet the sealing device safeguards the container from explosion by serving as an automatic release valve upon the buildup of excessive pressure in the container. The prevention of the entry of excess air into the container eliminates oxidation problems.

Then too, applicant's sealing device is inexpensive and easy of construction. It consists of only five parts, four of which may be stamped out. Thus the cap 14 may be formed of metal or plastic. The gasket 34 may be stamped out of sheets of rubber or neoprene. The valve element 20 preferably is molded out of a suitable plastic in one operation. Also the disc element 16. The compression spring 38 is readily available commercially. The sealing device is assembled by simply putting the parts together in the proper order. The parts, while simple, may be made durable, to provide trouble free operation.

Manifestly, the simpleness and inexpensiveness of the new sealing device will permit mass marketing techniques of the sealing device, per se, designed to banish forever the time loss and inconvenience and messiness attendant the present use of containers wherein container outlets must be manually opened before dispensing and manually closed thereafter. A further advantage in the use of the new sealing device is the elimination of breakage due to handling required for opening and closing of currently used containers.

It will be understood that there has been described in detail herein only a preferred embodiment of the invention. Other embodiments will be readily apparent to a person skilled in the art and it will be understood that various omissions and substitutions and changes in form and detail of the sealing device structure and operation may be made without departing from the spirit of the invention. It is intended, therefore, to be limited only by the scope of the following claims.

What is claimed is:

1. A sealing and dispensing device comprising a container attachable cap having a flat top formed with a central opening and a vent opening, a gasket formed of resilient material and having a central opening aligned with said central top opening and a vent opening for non-alignment with said central top opening and said top vent opening and disposed inside the top in said cap, a valve element disposed inside said gasket in said top and having a spaced peripheral portion formed with an opening and a flexible central portion extending from a point intermediate said periphery to a center which engages the walls of the gasket opening to close it off, a disc sealing element having an opening for alignment with said valve element opening and disposed inside said valve element in said cap to seal off a space inside said valve element central portion from container fluid pressures, said valve element being grooved to vent the space beneath said central portion, a compression spring disposed between the valve element central portion and the disc sealing element, said aligned openings in said valve element and said disc sealing element being intended to conduct container fluids under pressure to the space

above said valve element central portion to uncover the gasket central opening, said gasket upon the removal of container fluid pressures and the closing off of its central opening by the central portion under the action of the compression spring distending from the cap top to uncover the vent openings in the top and the gasket to facilitate the entrance of air to replace displaced fluid.

2. A sealing and dispensing device according to claim 1 mounted over the outlet of a container having flexible walls to be compressed to build up pressure in the fluid contents sufficient to open the sealing and dispensing device.

3. A sealing and dispensing device comprising means having a top portion for closing off an outlet to a container, said top portion having an opening, a valve element disposed inside said means and having an opening and a flexible central portion extending from a peripheral area spaced from said top portion towards which it is urged to close off said top portion opening, and a disc sealing element having an opening for alignment with said valve element opening juxtaposed to the underside of said valve element to seal a space beneath the valve element central portion from container fluid pressures, the openings in said valve element and said disc sealing element being intended to conduct fluid under pressure to the space above said valve element central portion to deflect said central portion and uncover said top portion opening, said top portion being flat and having a vent opening, and a gasket of resilient material formed with an opening for alignment with the top portion opening and a vent opening non-aligned with the first mentioned vent opening said gasket being disposed between the top portion and a portion of the valve element, and the walls of the opening of the gasket being engaged by the central portion of the valve element so as to have its opening closed off.

4. A sealing and dispensing device for a flexible receptacle having an outlet comprising an outer element having an opening, an inner element extending across said outlet and having a portion spaced from the outer element, said inner element being flexible and having another portion normally in contact with the outer element to close off its opening and movable away from said outer element to uncover its opening, means for communicating the outlet of a receptacle with the space between the outer and inner element, rigid means isolating an operating space behind the flexible inner element, means venting the operating space to the atmosphere and means associated with said communicating means to facilitate the entrance of air into the flexible receptacle to replace displaced fluid, said means including an element of resilient material distendable only upon the occurrence of a lower than atmospheric pressure inside the receptacle.

5. A sealing and dispensing device for a flexible receptacle having an outlet comprising a first element and a second element spaced therefrom, said elements respectively extending across said outlet, one of said elements being flexible and having a portion normally in contact with the other element to close off an opening in one of them and movable away from the other element to uncover said opening, means for communicating the outlet of a receptacle with the space between the first and second element, and further means for communicating the outlet with the atmosphere, said further means only being operative to facilitate the entry of air into the receptacle upon termination of flexure of the flexible element and including an element of resilient material distendable only upon the occurrence of a lower than atmospheric pressure inside the receptacle.

6. A sealing and dispensing device for a flexible receptacle having an outlet comprising a first element and a second element spaced therefrom, said elements for respectively extending across said outlet, one of said elements being flexible and having a portion normally in

contact with the other to close off an opening in one of them and movable away from the other to uncover said opening, means for communicating the outlet of a receptacle with the space between the first and second element, said flexible element being exposed at all times on its side exterior of the space between the first and second element to atmospheric pressure to facilitate uncovering movement, and further means for communicating the outlet with the atmosphere, said further means only being operative to facilitate the entry of air into the 10 receptacle upon termination of flexure thereof and including an element of resilient material distendable only

upon the occurrence of a lower than atmospheric pressure inside the receptacle.
